DESIGN FOR A SCRUB BUCKET

Florence Elizabeth Groves, Beckenham, England

Application August 26, 1939, Serial No. 86,907

Term of patent 7 years

To all whom it may concern:

Be it known that I, Florence Elizabeth Groves, a subject of the King of England, residing at Beckenham, in the county of Kent, in the Kingdom of England, have invented a new, original, and ornamental Design for a Scrub Bucket, of which the following is a specification, reference being had to the accompanying drawing, forming part thereof.

The figure is a perspective view of one side of a scrub bucket showing my new design. The other side of the bucket is substantially like the side shown.

The design is characterized by the brackets on the lower sides of the bucket, of the contour and arranged as shown.

I claim:

The ornamental design for a scrub bucket, as shown and described.

FLORENCE ELIZABETH GROVES.
